UNITED STATES PATENT OFFICE.

OWEN E. WRIGHT, OF HURON, SOUTH DAKOTA.

EXTERIOR CRANK-CASE OIL HEATER.

Application filed July 18, 1923. Serial No. 652,392.

To all whom it may concern:

Be it known that I, OWEN E. WRIGHT, citizen of the United States, residing at Huron, in the county of Beadle and State 5 of South Dakota, have invented certain new and useful Improvements in Exterior Crank-Case Oil Heaters, of which the following is a specification.

This invention relates to an improved exterior oil heater for engine crank cases and seeks, among other objects, to provide a device which will, in cold weather, prevent the chilling of the oil in an engine crank case and thus overcome otherwise faulty 15 lubrication due to viscosity of the oil.

The invention seeks, as a further object, to provide a device which may be readily applied over the engine crank case and connected with the exhaust pipe of the engine 20 so that the heat from the engine exhaust gases will be utilized for heating the crank case.

And the invention seeks, as a still further object, to provide a device which, while being particularly adapted for use upon Dodge engines, may also be employed upon engines of other makes.

Other and incidental objects will appear hereinafter.

30 In the drawings:

Figure 1 is a side elevation showing my improved heater applied to a Dodge engine,

Figure 2 is an enlarged elevation, the heating pan employed being broken away 35 and shown in section,

Figure 3 is a transverse sectional view on the line 3-3 of Figure 2, looking in the direction of the arrows, and

Figure 4 is a detail perspective view of 40 the heating pan.

Referring now more particularly to the drawings, I have, for convenience, shown my improved heater in conjunction with a Dodge engine embodying the usual cylinder 45 block 10 having flanges 11 and connected to said flanges is an oil pan 12. The pan 12 is provided with flanges 13 abutting the flanges 11 and extending through said flanges are cap bolts 14. The usual oil pump 50 of the engine is indicated at 15 and connecting the pump with the oil pan 12 is a pipe 16. The exhaust pipe of the engine is indicated at 17.

Coming now more particularly to the 55 subject of the present invention, I employ a heating pan or jacket 18 which is formed

to removably fit snugly about the rear end portion of the oil pan 12. The heating pan is preferably constructed of suitable sheet metal and is provided with a bottom wall 19 from which extend upwardly convergent 60 side walls 20 provided at their upper ends with laterally directed flanges 21 seating flat against the flanges 13 of the oil pan 12. As brought out in Figure 4, the flanges 21 are apertured to accommodate three of the cap bolts 14 which bolts are utilized for connecting the heating pan with the engine. Thus, the necessity for separate fastening 70 devices for the heating pan is eliminated while, by removing the proper cap bolts of the oil pan, the heating pan may be readily applied, the cap bolts removed being each, of course, again inserted through the flanges 75 of the heating pan and through the flanges of the oil pan, as shown in Figure 3, for tightly securing the heating pan in place. Extending between the side walls 20 of the heating pan is a front wall 22 provided with a downwardly curved upper edge 23 to fit 80 the oil pan 12 immediately in front of the pump 15 and formed in said front wall is an opening 24 to accommodate the oil pipe 16. In applying the device, the oil pipe 16 is, of course, first detached so that said oil pipe 85 may be inserted through the opening 24 and later connected to the pump after the heating pan has been secured in position. Extending between the side walls 20 of the heating pan in spaced parallel relation to 90 the front wall 22, is a back wall 25 which, like the wall 22, is also cut away, as particularly shown in Figure 3, to fit the oil pan 12. In this connection, it is to be noted that said oil pan gradually slopes downwardly to a maximum depth at a point behind the pump 15 and then rises abruptly 95 toward the pump. Accordingly, the back wall 25 is formed with a corresponding opening 26 to accommodate the downwardly 100 sloping portion of the pan, the opening 26 being provided with downwardly converging side walls to snugly fit the sides of the pan and with a straight bottom wall to snugly fit the bottom of the pan. At its 105 deepest portion, the oil pan 12 forms, of course, a sump for the crank case oil and, as will now be seen, the heating pan 18 cooperates with the oil pan to form a jacket 110 housing said sump.

Surrounding the exhaust pipe 17 is a collar 27 communicating with the pipe and

connected to said collar is a pipe 28 which may be either rigid or flexible, as preferred. Mounted upon the back wall 25 of the heating pan 18 at one side thereof is an inlet nipple 29 removably accommodating the forward end of the pipe 28 and mounted upon said wall near the opposite side of the pan is a downwardly directed outlet pipe 30. Mounted upon the collar 27 is an appropriate valve 31 to the lever of which is attached a rod 32 which may be operated from the driver's seat of the vehicle for opening or closing the valve. Thus, while the engine is running, exhaust gases may be diverted through the pipe 28 into the heating pan 18 to circulate around the oil pan 12 when said gases will discharge through the outlet pipe 30. Accordingly, the oil in the sump of the oil pan will be kept heated and, therefore, maintained in a fluent condition. I thus provide a device which will overcome all the trouble heretofore experienced due to chilling of the crank case oil and while I have illustrated and described the device in connection with a Dodge engine, still, as will now be seen, the device may be readily adapted to engines of other makes.

Having thus described the invention, what is claimed as new is:

30. 1. The combination with an internal combustion engine having a cylinder block, a crank case provided with an oil sump, and fastening means connecting the crank case with said block, of a heating pan removably secured about the crank case by said fasten-

ing means to form a jacket housing said sump, and means for diverting exhaust gases through said jacket.

2. The combination with an internal combustion engine having an oil pan, and an oil pump pipe extending exteriorly of the oil pan and exposed to the atmosphere, of a heating pan fitting the oil pan to provide a heating jacket housing a portion of said pipe for protecting the pipe and confining exhaust gases to direct contact therewith, and means for diverting exhaust gases through said jacket.

3. In a crank case oil heater for internal combustion engines, a heating pan having side and bottom walls and front and back walls, the front and back walls being cut away to fit an engine oil pan embraced by said side walls and the side walls being formed with overhanging flanges apertured to receive bolts securing the oil pan to the engine.

4. The combination with an internal combustion engine having a cylinder block, a crank case provided with an oil sump, and bolts connecting the crank case with said block, of a heating pan removably secured about the crank case by said bolts to form a jacket housing said sump and having side walls provided with overhanging flanges accommodating the bolts therethrough, and means for diverting exhaust gases through said jacket.

In testimony whereof I affix my signature.
OWEN E. WRIGHT. [L. s.]
